(57) **CLAIM**

The ornamental design for a speaker housing with shield, as shown and described.

DESCRIPTION

FIG. 1 is a front perspective view of a portion of a speaker housing with shield showing my new design,

FIG. 2 is a front elevational view thereof,

FIG. 3 is a right side elevational thereof,

FIG. 4 is a left side elevational view thereof; and,

FIG. 5 is a top view thereof.

The broken line showing of the remainder of the speaker housing is for illustrative purposes only and forms no part of the claimed design. The unshown portions of the housing form no part of the claimed design.
